UNITED STATES PATENT OFFICE.

CHARLES LAFFITE, OF PARIS, FRANCE.

PANTALOON-BRACE.

SPECIFICATION forming part of Letters Patent No. 230,289, dated July 20, 1880.

Application filed April 28, 1880. (Model.) Patented in France February 21, 1880, in Belgium February 23, 1880, and in England February 23, 1880.

To all whom it may concern:

Be it known that I, CHARLES LAFFITE, of Paris, France, have invented an Improvement in Pantaloons-Braces, of which the following is 5 a specification.

The invention consists in providing the suspender-ends with short transverse straps or chains, as hereinafter described.

Figures 1, 2, 3 of the drawings show the 10 front end of suspenders; and Fig. 4, the rear end with my improvement.

In the drawings, A represents the bands or straps which pass over the shoulders and are provided in front with a loop, B, and in the 15 rear with a fold, F. I take a chain or cord, C, which is provided at each end with a button, D, or a detachable pin, K, or a hook, E, or a double-head button, L, and pass it through the loop B or fold F, so as to connect by button-holes M with the belt G of the pantaloons.

N is a cross chain or cord, by which I connect the two sides of the part C, and thus prevent too much play, as well as the slipping through the loop.

Having thus described all that is necessary 25 to a full understanding of my invention, what I claim as new is—

In pantaloons-braces, the combination, with the loop B, of the chain C and the transverse chain N, substantially as and for the purpose 30 specified.

The above specification of my invention signed by me this 17th day of March, 1880.

CH. LAFFITE.
